ROCK DRILL CUTTING INSERT OF HARD METAL

Didrik Wilhelm Haglund, Sandviken, Sweden, assignor to Sandvikens Jernverks Aktiebolag, Sandviken, Sweden, a corporation of Sweden

Application July 6, 1955, Serial No. 520,307

4 Claims. (Cl. 255—63)

This invention relates to rock drill cutting inserts formed of hard metal.

By "hard metal" is meant a sintered alloy consisting essentially of one or more carbides and/or other hard materials, for instance tungsten carbide, combined with one or more bonding metals such as cobalt or other metals of the iron group.

The cutting inserts of this invention are designed to give a greater amount of drilling per unit of hard metal and are characterized in that they consist of zones having different degrees of toughness and wear resistance as a result of difference in grain size and/or chemical composition, at least one of said zones of greater toughness increasing in cross-sectional area in the direction away from the cutting edge or toward the bottom of the insert.

For best performance rock drill cutting inserts must have a high resistance to wear as well as a satisfactory mechanical strength—toughness—in order to avoid breaking and crumbling under the great shock strains which are applied during boring with a modern percussion drilling machine. The cutting insert therefore in itself has to combine the highest possible resistance to wear and toughness.

However, it is very difficult to combine these two qualities in a hard metal cutting insert of the homogeneous type, by which is meant cutting inserts with uniform grain size and/or chemical composition. Thus if hardness and consequently also resistance to wear is increased the cutting insert becomes more brittle, and conversely if the toughness and consequently the mechanical strength is increased the cutting insert becomes less resistant to wear.

Therefore it has been suggested heretofore to produce hard metal cutting inserts with zones of different resistance to wear. The more wear resistant material is placed at the ends of the cutting insert at the periphery of the drill bit or in one or more relatively thin zones arranged parallel with the side surfaces of the cutting insert. The more wear resistant material usually has a lower content of bonding metal than the more tough one. Further it is known that a difference in resistance to wear may be accomplished through suitable choice of carbides or through suitable choice of grain size in the hard metal.

In comparison with the earlier known cutting inserts, both the homogeneous as well as those of the compound type, the cutting insert according to the present invention gives a substantially increased resistance to wear and strength.

The invention is based upon the following considerations. If the cutting insert consists of a hard, highly wear resistant hard metal its remaining height after a certain number of bore meters is greater than that of a cutting insert with a less wear resistant, tougher hard metal. In other words the tough material wears away faster than the harder material. The tougher cutting insert may, however, be worn down to a lower insert height than the harder and more wear resistant insert

2

before it breaks on account of the mechanical stresses. The advantages of both the more wear resistant and the tougher cutting inserts are combined in the same cutting insert by positioning the different types of hard metal so that more of the tougher type is brought into the cutting surface of the insert as the cutting insert wears away. Thus the more wear resistant hard metal is used when the insert height is still great, but the tougher hard metal is used more and more as the insert height approaches the zone of danger of breakage on account of the mechanical stresses.

A further advantage of the cutting insert according to the invention is that the position of the more wear resistant hard metal prevents the formation of a so-called counter peg at the periphery of the drill bit. Such a counter peg is usually formed in certain species of rock and not only prevents the advance of the drill bit but also frequently causes breakage of the cutting inserts.

Variations in resistance to wear and toughness for the different zones in the cutting insert according to the invention may be obtained in a known manner, either by a variation in grain size or by a variation in analysis or by a simultaneous variation both in grain size and analysis. At the same analysis the more fine-grained material usually forms the more wear resistant harder zone or zones while the more coarse-grained material provides the tougher zone or zones.

The invention will now be further described in connection with the accompanying drawings which show a number of embodiments of cutting inserts in accordance with the invention.

Fig. 1 is a perspective view of a rock drill bit provided with a hard metal cutting insert;

Figs. 2 and 3 are side and end views respectively of a cutting insert;

Figs. 1—14 show different embodiments in cross-section on the line A—A in Fig. 2; and

Figs. 15—17 and Figs. 18—20 show different embodiments in longitudinal section along the line B—B of Fig. 2 and the line C—C of Fig. 8 respectively.

The drill bit 10 shown in Fig. 1 is provided with a hard metal insert 11 fastened into a groove by means of brazing or in any other suitable way. The drill bit may be provided with more cutting inserts, for example four inserts arranged in cross-form, and the cutting inserts may be divided into two or more separate parts as is well known in the art. The invention is not limited to the plate-like form of the cutting insert, shown in Fig. 1, which insert may have any other known form within the scope of the appended claims. Thus the cutting insert may have converging side surfaces in boring direction.

In all of the embodiments illustrated 12 is the more wear resistant and usually also the harder part and 13 is the tougher part. In Figs. 4—14, which show sections perpendicular to the longer axis of the cutting insert illustrate several different ways in which the hard metal zones may be arranged. According to Figs. 4—10 the more wear resistant hard metal 12 is substantially wedge shaped with the side boundaries converging downwardly toward the base of the insert. The side boundaries of the wedge-shaped portion are completely surrounded by the tougher hard metal. Figs. 11—14 on the other hand show the tougher portion wedge-shaped with the side walls converging upwardly toward the cutting edge of the insert and embedded in the more wear resistant portion. As appears in all of the figures the major part of the cutting edge of the insert is formed by the more wear resistant part of the insert. This more wear resistant part of the insert may extend down to the bottom of the insert where the major part of the insert consists of tougher material (Figs. 4—7, and 9 and 12) or terminate at a substantial distance above the bottom of the insert (Figs.

8, 10, 11, 13 and 14). The more wear resistant as well as the tougher portions of the insert may terminate in an edge (Figs. 5, 6 and 12) or may be more or less blunt for example of a blunt or rounded form (Figs. 4, 7, 11, 13 and 14). Further it may be advantageous to provide at least three zones 12, 14 and 13 with successively increasing toughness away from the cutting edge (Fig. 10 and 14) or to merge the more wear resistant material substantially continuously into the tougher material so that the toughness of the cutting insert as a whole increases in the direction from the cutting edge or face toward the bottom of the insert. The inclined surfaces of the wedge-shaped parts of the inserts should be at an angle to each other of more than 20° and preferably at least 30°.

By choosing a suitable grain size and/or analysis for the different zones of the insert the desired qualities of great wear resistance in the upper part and a good toughness in its below part may be provided. Usually the cutting insert consists of a sintered unit and the boundaries between the zones may be sharply defined or they may show a more or less continuous mergence. It is also possible to manufacture the different zones separately and then unite them in a suitable way, for instance by brazing.

As an example of different grain sizes in the different zones of a cutting insert with substantially the same analysis throughout, the grain size for the more wear resistant zone or zones may be between 1 and 2 to 2.5 microns and for the tougher zone or zones between 3 and 6 microns or 4-5 microns. In this example the composition may be 91-94%, preferably 93% WC, and 6-9% preferably 7% of Co. As mentioned above the difference in resistance to wear and toughness may also be provided for by selection of the composition, for example the cobalt content, which for the more wear resistant zone may be chosen for instance between 5 and 9% and for the tougher zone for instance between 10 and 15%. This variation in composition may be combined with variation in grain size.

Figs. 15-17 show a section in the longitudinal direction of the cutting insert parallel with the bottom surface, which is indicated by the line B—B in Fig. 2. As appears from these figures the more wear resistant zone or zones 12 extend to the end surfaces of the cutting insert and may either extend along the whole length of the cutting insert (Fig. 15) or may be divided into two or more zones in the longitudinal direction of the cutting insert, separated by tougher hard metal 13 as shown in Figs. 16 and 17. The tougher hard metal may form the bottom layer as well as the central part of the cutting insert. Figs. 18-20 show alternative embodiments of the cutting insert in accordance with the invention seen in a longitudinal section along the line C—C of Fig. 8. The lower boundary of the more wear resistant zone or zones may be parallel with the bottom of the insert (Fig. 18), upwardly convex as shown in Fig. 19, angular as shown in Fig. 20 or polygonal.

In comparison with earlier used cutting inserts the inserts according to the invention give a very high resistance to wear during the whole useful life and they can be worn down considerably thinner than has hitherto been possible. The result is a considerably increased amount of drilling per bit.

In Figs. 2 and 6 the dotted lines *a—a*, *b—b* and *c—c* show different stages of the wearing down of the cutting insert. It appears from these lines how the ratio between the tougher and the more wear resistant zones increases as the cutting insert is worn down but the cutting edge during the whole wearing down period consists of the more wear resistant hard metal. When the height of the insert has been reduced to the point where there is a risk of breakage on account of the mechanical stresses the remaining part of the cutting insert substantially consists of the tougher material. In comparison with earlier cutting inserts this point at which the insert must be discarded due to danger of breakage is considerably lower. As an example may be mentioned that the cutting height for the normally used cutting inserts in drilling a certain kind of rock is 10 to 15 mm. whereas the cutting inserts according to the invention may be worn down to about 3 to 5 mm.

The invention is not limited to the described and shown embodiments but embraces every rock drill cutting insert within the scope of the following claims.

I claim:

1. A rock drill cutting insert having a cutting edge surface, a plane bottom surface opposite to said cutting edge surface, oppositely disposed substantially parallel plane side surfaces and oppositely disposed end surfaces, said insert consisting of at least one zone of hard metal which has a relatively greater resistance to wear and at least one zone which has a relatively greater toughness, said zone which has a relatively greater resistance to wear constituting substantially the whole of said cutting edge surface and extending downwardly therefrom with a decreasing cross sectional area in the direction from said cutting edge surface toward said bottom surface, said zone which has a relatively greater toughness constituting the remainder of the insert and extending upwardly with a decreasing cross sectional area in the direction from said bottom surface toward said cutting edge surface, the lateral boundary surfaces between said zones being substantially plane surfaces and lying at acute angles to the adjacent side surfaces of said insert.

2. Rock drill cutting insert according to claim 1, characterized in that the zone of greater toughness successively increases in cross sectional area in at least a substantial part of the insert in the direction from the cutting edge surface towards said bottom surface.

3. Rock drill cutting insert according to claim 1, characterized in that said boundary surfaces are inclined toward each other with an angle between the surfaces of more than 20°.

4. Rock drill cutting insert according to claim 3, characterized in that at least one of said zones tapers to an edgelike configuration.
